FLOW CONTROL FOR PLUNGER LIFT
DEVICESHenry B. Woods, Houston, Tex., assignor to
Hughes Tool Company, Houston, Tex., a cor-
poration of Texas

Application July 25, 1932. Serial No. 624,460

5 Claims. (Cl. 103—52)

My invention relates to plunger lift devices, and pertains particularly to the flow line through which the fluid issues from the well.

I desire to control the flow of the liquid from the well, so as to check the rush of gas or air employed in raising the load.

It is an object of the invention to provide a choke device in the flow line and enlarge the capacity of the line between the eduction tube 10 and the choke so that it may include the whole load of liquid and impede the outlet for the gas or air behind the plunger and thus stop the flow of gas until the plunger can drop to the bottom of the tube without interference from the gas.

15 I aim to clear the tube of its load of liquid and then check the escape of the gaseous pressure fluid through the liquid in the flow line, until the plunger has had time to drop back to the bottom of the eduction tube.

20 In the drawing herewith, Fig. 1 is a side view mostly in central vertical section of a plunger lift device equipped with my invention.

Fig. 2 is a central vertical section through the lower end of the well with the eduction tube 25 therein.

Fig. 3 is a side view partly in elevation and partly in longitudinal section of a slightly different embodiment of the invention.

In Figs. 1 and 2 the usual form of the plunger lift device is seen with my improvement installed thereon. It has a well casing 1 with a casing head 2 thereon. The eduction tube 3 is supported in the casing head and depends to the fluid level in the well. A strainer plug 5 at the lower end 35 is connected to the tube by a coupling 4, having therein a cross shaped stop member 6.

The upper end of the tube has a head 7 thereon supported upon a flange 8 in the casing head and forming a seal therewith. Above the head 7 the tube is perforated at 9 to form an outlet for fluid to the interior chamber 10 within the casing head. From there the liquid passes by way of the flow line 11 to storage. This flow line is made of large capacity and the choke valve 12 is placed far enough from the casing head to allow room in the flow line to receive all the liquid load raised by the plunger at one stroke. This load is, however, prevented from flowing past the choke formed by the needle valve 12 except at a very slow rate. A by-pass line 13, having therein a hand operated valve 14, is provided from the inlet end of the flow line to a point past the choke valve 12.

The upper end of the eduction tube forms an 55 extension projecting above the bonnet 15 as seen

at 16 and closed at its upper end by a cap 17, having therein a compressible tubular shock absorber 18. A vent 19 is provided at the upper end controlled by a valve 20.

The plunger is shown at the lower end of its 60 stroke. It comprises a body member 21 having an inner downwardly tapered passage and a valve 23 closing upwardly into a seat in said passage. A support for the valve is formed at 22 to support the valve in open position and 65 acting also as a guide for the stem of the valve which extends through the support to engage the stop 6 and close the valve.

In operation the plunger, with its load of liquid 70 is moved upwardly by gas accumulating in the well. The load of liquid above the plunger will be discharged through the flow line but will be checked in its flow by the choke valve 12. The capacity of the flow line between the casing head and the choke valve being sufficient to include all the load of liquid, the plunger may pass 75 the outlet and be stopped by the fluid—both gas and liquid—in the extension 16. The valve in the plunger will be forced open and the plunger will drop to the bottom. The flow of gas from 80 the well will be checked so that it will not interfere with the dropping of the plunger. The flow in the main flow line will be stopped temporarily until the liquid has time to pass the choke valve. A slight flow of gas is allowed through the by- 85 pass 13 to relieve the gas pressure in the well so that liquid may enter the lower end of the well for the next load. Thus when the plunger reaches bottom there will be a load of liquid 90 above the seat and the plunger will sink through the liquid to its seat where the valve stem in the plunger will engage the stop member 6 and close the valve ready for the next stroke.

By the time the plunger has reached bottom 95 the liquid will have passed the choke valve 12 and the gas in the eduction tube will quickly exhaust from the tube and hence prevent back pressure on the plunger in raising its next load.

In Fig. 3, I have shown an apparatus intended 100 to be, in all respects, the same as the first described embodiment except that the capacity of the flow line between the casing head 2 and the choke valve 12 is increased by the use of a special chamber 25 connected into said flow line. Thus, instead of making the flow line long, between the casing head and choke, it may be made short as here shown, but the chamber 25 will contain most of the liquid load so that the gas may be largely cut off from the flow line and its escape 105 slowed down to allow the plunger to fall unim- 110

peded by the rush of gas which would otherwise take place.

By the use of my arrangement of the apparatus, the liquid above the plunger is discharged 5 from the eduction tube, but the flow of gas from the tube is prevented for a time sufficient to allow the plunger to reach bottom. By that time the gas can exhaust rapidly.

In this way I not only speed up the dropping 10 of the plunger and hence the operation of the pump, but I economize in gas consumption. For, as the gas pressure in the well is not relieved materially while the plunger is falling, there will be but little gas bubbling up through the liquid at 15 the well bottom and escaping while the plunger is falling.

What I claim as new is:

1. A plunger lift device including a well casing, an eduction tube therein, a plunger movable 20 from the lower end to the upper end thereof by pneumatic pressure, an outlet from said tube and casing, and a flow line in said outlet, in combination with a choke valve in said flow line set to allow a continuous flow of liquid therethrough, 25 said flow line being of large capacity between said outlet and said valve to include the entire load of liquid raised by the plunger, said choke valve arranged to allow the slow passage of said liquid.

2. A plunger lift device including a well casing, 30 an eduction tube therein, a plunger movable by pneumatic pressure from the lower end to the upper end of said tube, a flow line receiving the fluid from said tube, a choke valve in said flow line, and a container formed in said flow line 35 between said eduction tube and said choke valve to contain the entire load of liquid raised by the plunger at each stroke, said choke allowing the slow discharge of said load.

3. In a plunger lift device including an eduction tube, a plunger movable by pneumatic pressure to raise a load of liquid from the lower end to the upper end of said tube, and a flow line from said tube below the upper end of said tube, the improvement consisting of closing the outlet of all but a small flow of gas from the tube by use of the load of liquid, until said plunger has dropped to the lower end of said tube and then opening said flow line to said gas.

4. A method of raising liquid from deep wells containing a body of liquid and a seepage of gas thereinto consisting of interposing a plunger between the bottom of a column of liquid in the well, and a gas receiving space under said column and employing the gas pressure below said plunger to force said plunger and its load of liquid to the upper end of said tube, discharging said load of liquid, maintaining said liquid at the discharge outlet until said plunger has fallen in said well and then exhausting the gas from the liquid discharge outlet.

5. A method of raising liquid from deep wells containing a body of liquid and a flow of gas thereinto, consisting of interposing a plunger between the bottom of a column of liquid in the well and a gas receiving space under said column, and employing said gas pressure below said plunger to raise said plunger and its load of liquid to the upper end of said tube, discharging said liquid from the outlet from said well, blocking the outlet of all but a small amount of gas from said well by use of said liquid until said plunger has fallen a predetermined amount, then opening said outlet to allow free escape of said gas.
